STOKER

Frank P. Roesch, Chicago, Ill., and George R. Stewart, Denver, Colo., assignors to The Standard Stoker Company, Incorporated, a corporation of Delaware

Application April 19, 1932, Serial No. 606,086

17 Claims. (Cl. 110—101)

This invention relates generally to mechanical stoking means for delivering fuel from a source of supply to the firing opening of a boiler furnace, thereby scattering the fuel in aerial paths over the fire, and more particularly, to the fuel distributing means of stokers of the type described.

The principal object of the invention is to provide an improved form of distributor plate and means for adjusting the same, and more specifically, 10 a distributor plate, mounted at the mouth of a fuel discharge box, which is rotatable about the longitudinal axis of the plate itself and which is provided with simple, conveniently accessible, and efficient means for adjusting and securing 15 the distributor plate in angular relation with the discharge box.

With the above and other objects in view, the invention consists of the novel details of construction and operation, and the combination and arrangement of parts, a preferred embodiment of which is described in the specification and illustrated in the accompanying drawings, wherein

Figure 1 is a view in side elevation of the forward portion of a mechanical stoker applied to a "skidder" boiler;

Figure 2 is a vertical central section of the discharge end of a mechanical stoker and the distributor therefor;

Figure 3 is a front end elevation of the discharge end of the stoker;

Figure 4 is a detail sectional view of the distributor plate adjusting means;

Figure 5 is an isometric view of the distributor plate;

Figure 6 is an isometric view of the distributor head; and

Figure 7 is a section on the line 7—7 of Figure 3.

This invention is particularly advantageous in stoker installations on "skidders" and will be described with reference to such an installation, but it will be obvious as the description proceeds that the invention is of a broader nature and may be applied to locomotive stoker and other installations.

A "skidder" generally comprises a car frame arranged to be rolled from place to place on a track, having a deck 10, a vertical boiler 11 provided with a fuel feed opening 12, and mechanism, power for which is generated by the boiler 11, arranged to operate drag lines for logging out timber. The latter mechanism forms no part of the present invention and for that reason is neither shown in the drawings nor further described.

During operation of the "skidder", that is, when the timber within reach of the drag lines is being dragged in, the boiler leans to the right or left depending upon whether the area to the right or left of the "skidder" is being logged. Thus, when for example, the area to the right of the "skidder" is being logged, and this may require a week or two, the boiler leans to the right, and in mechanical firing of the boiler, the stoker discharge box, which is attached to the boiler, and the distributor plate will lean to the right. As a result, more of the coal is delivered onto the distributor plate from the right side of the discharge box and it follows that more of the coal is distributed over the right side of the boiler firebox. In a similar manner more coal is delivered to the left side of the boiler firebox when the area to the left of the "skidder" is being logged. The disadvantages and objections inherent in such a construction are entirely eliminated by the present invention.

The stoker mechanism for delivering fuel to the boiler 11 includes a transfer conduit system, the forward end of which is shown and designated by the numeral 13, of a suitable design and construction and leading from a suitable source of fuel supply (not shown). A forward curving conduit or riser conduit 14 communicates at its upper end with the firing opening 12 and extends rearwardly and downwardly through the deck 10 terminating at a point therebelow. The riser conduit 14 is rigidly secured to the boiler 11 by a bracket 15 and at its lower end is provided with a spherical seat 16 receiving the ball member 17 of the transfer conduit 13.

The riser conduit 14 flares outwardly towards its upper end and communicates with the firing opening 12 through its laterally spreading and substantially horizontal discharge box or mouth portion 18. This mouth portion 18 is provided with laterally extending flanges 19 for attachment to the boiler 11 by suitable fastening means. The lower wall of the mouth portion 18 terminates adjacent, but rearwardly of the firing opening and has its forward face recessed or cut away as at 20 to receive the rear end of the distributor plate 21 and the blast means or distributor head 22. The distributor plate 21 is detachably fastened to the forward face 20 of the recessed portion of the lower wall of the conduit mouth portion 18, in a manner to be described hereinafter in more detail, and forms a continuation of the said lower wall.

The end wall 21 of the plate 21 is provided with an indentation 22 intermediate the sides 23

- of the plate. Fitted in the indentation 52 of the plate 21 and outside the boiler 11 is the vertically disposed nozzle or distributor head 22 to which pressure fluid such as steam is supplied by a desirable number of supply pipes 23. The distributor head 22 is provided with openings or jets 24 in a horizontal row for emitting a blast of fluid across the distributor plate 21. The riser conduit 14 is provided with a removable cover section 25 which may be hinged at its upper end and held in closed position by a latch 26 whereby access may be had to the interior of the riser conduit.
- The distributor head 22 is securely attached to the distributor plate 21 by the bolts 27, whereby the plate and distributor head are always maintained in the same relative position with respect to each other. Formed with the rear wall of the distributor head 22 and extending rearwardly thereof in alignment with the longitudinal center line of the distributor plate is a pivot pin or circular lug 28 which is received in the circular recess 29 in the forward face 28 of the lower wall of the riser conduit discharge box or mouth portion 18. The distributor plate and distributor head are secured to the riser conduit discharge box or mouth portion by the bolts 30 passing through the vertically elongated arcuately shaped slots 31.
- When for example, the boiler 11, to which is attached the riser conduit 14, is leaning to the right, the obvious result is that more coal will be delivered to the right side of the distributor plate and consequently to the right side of the boiler firebox. However, in the present construction, under such circumstances, the bolts 30 are loosened and the distributor plate is rotated counterclockwise about its longitudinal center line, which is determined by the axis of the pivot pin 28, to assume a horizontal position or even tilted to the left. Since the slots 31 are elongated and slightly arcuate in shape, the distributor plate may be turned at an angle with respect to the riser conduit, without removing the bolts 30, and when the plate is placed in the desired position, the bolts are tightened, again securing the plate and distributor head to the riser conduit mouth portion. The result of this arrangement is that when the plate is tilted in the desired position, the right side of the distributor head 22 projects above the level of the floor of the discharge box or mouth portion 18 a certain amount, the other side of the plate being lowered a corresponding amount. Therefore, even though more coal is brought up on the right side of the discharge box or mouth portion, the distributor head 22 acts as a dam or obstruction and holds back the excess of coal, which now must overflow that side of the distributor head before it can fall onto the distributing plate. This then permits an even delivery of coal onto the plate, and consequently, an even distribution of coal over the boiler firebox. To insure a close fit between the lower wall of the discharge box mouth portion 18 adjacent the recess 50 and the distributor plate sidewalls and still permit rotation of the plate, the sides of the plate adjoining its end wall 51 are provided with the curvate surfaces 53 and the sides of the recess 50 are correspondingly curved.
- Particularly devised and arranged means are provided for rotating the plate from without the riser conduit mouth portion. This means includes a horizontal flange 32 extending laterally from a sidewall of the discharge box or mouth portion 18, provided with an opening 33. A nut

34 is received in the opening 33 and is provided with the flanges 35 and 36 engaging the marginal top and bottom edges of the flange 32 defining the opening 33. The nut 34 is preferably composed of two interthreaded members 37 and 38 for assembly purposes. Sufficient clearance is permitted between the nut 34 and the marginal edges of the flange 32 defining the opening 33, to permit the nut 34 to be loosely mounted thereon.

The nut 34 has a threaded opening 39 therethrough for receiving a threaded stud 40, which is arranged to move up when the nut 34 is turned in one direction and down when the nut 33 is turned in the opposite direction. Movement of the threaded stud 40 is in turn communicated to the transversely extending stud 41 which is threaded into the side of the distributor plate 21. Thus by turning the nut 34 thereby raising or lowering the threaded stem 40, the distributor plate is rotated about its longitudinal center line. 20

We claim:

1. In a furnace provided with a firing opening, a fuel discharge box communicating with said firing opening, a fuel distributing device, including a plate-like member and means for projecting fuel thereover, extending forwardly from said discharge box and arranged to receive fuel therefrom, said fuel distributing device being arranged to be adjustable as a unit pivotally about its longitudinal center line, said member and said means remaining in the same relative position with respect to one another.

2. In a furnace provided with a firing opening, a fuel discharge box communicating with said firing opening, a fuel distributing device, including a plate-like member and means for projecting fuel thereover, extending forwardly from said discharge box through said firing opening, said fuel distributing device being arranged to be adjustable as a unit pivotally about its longitudinal center line, and means for securing said fuel distributing device rigidly in its adjusted position.

3. In combination, a furnace provided with a firing opening, a fuel discharge box communicating with said opening, a distributor plate extending forwardly from said discharge box and arranged to receive fuel therefrom, said plate being provided with a recess in its central rear portion, a distributor head fitted in said recess and arranged to issue a blast of pressure fluid across said distributor plate, means for rigidly securing said plate and head together, said distributor plate and distributor head being arranged for adjustment as a unit pivotally about their common longitudinal center line.

4. In a furnace provided with a firing opening, a fuel discharge box communicating with said firing opening, the lower wall portion of said discharge box having a transversely extending front face and a circular recess in said front face of said lower wall portion, a fuel distributing device having a rearwardly extending circular lug received in said circular recess forming a pivot for said fuel distributing device, said fuel distributing device being secured to said discharge box and adjustable with respect thereto.

5. In a furnace provided with a firing opening, a fuel discharge box communicating with said firing opening, the lower wall portion of said discharge box having a transversely extending front face, and a circular recess in said front face of said lower wall portion, a fuel distributing device having a rearwardly extending circular lug received in said circular recess forming a pivot for said distributing device, means for adjusting

said fuel distributing device about said pivot and means for rigidly securing said fuel distributing device to said discharge box in its adjusted position.

5. In a furnace provided with a firing opening, a fuel discharge box communicating with said firing opening, the lower wall portion of said discharge box having a transversely extending front face, and a circular recess in said front 10 face of said lower wall portion, a distributor plate extending forwardly from said discharge box and arranged to receive fuel therefrom, said plate being provided with a recess in its central rear portion, a distributor head fitting in said 15 last named recess, means for rigidly securing said distributor plate and distributor head together, said distributor head having a rearwardly extending lug received in said circular recess forming a pivot for adjustment of said distributor 20 plate and distributor head with respect to said discharge box.

7. In a furnace provided with a firing opening, a fuel discharge box communicating with said firing opening, the lower wall portion of said discharge box having a transversely extending front face, and a circular recess in said front face of said lower wall portion, a distributor plate extending forwardly from said discharge box and arranged to receive fuel therefrom, said plate being provided with a recess in its central rear portion, a distributor head fitting in said last 25 named recess, means for rigidly securing said distributor plate and distributor head together, said distributor head having a rearwardly extending lug received in said circular recess forming a pivot for adjustment of said distributor plate and distributor head with respect to said discharge box in its adjusted position.

8. In a furnace provided with a firing opening, a fuel discharge box communicating with said firing opening having its lower wall portion provided with a transversely extending front face, said front face being recessed and having a circular cavity in the front face of said recessed portion, a distributing device fitted in said recess, comprising a distributor plate and a distributor head, said distributor head being secured rigidly with the rear of said distributor plate and having a circular lug extending rearwardly therefrom and arranged to be received in said circular cavity forming a pivot for adjustment of said distributor plate and distributor head with respect to said discharge box.

9. In a furnace provided with a firing opening, a fuel discharge box communicating with said firing opening having its lower wall portion provided with a transversely extending front face, said front face being recessed and having a circular cavity in the front face of said recessed portion, and a distributing device fitted in said recess, said distributing device having a rearwardly extending circular lug arranged to be received in said circular cavity forming a pivot for adjustment of said distributing device with respect to said discharge box.

10. In a furnace provided with a firing opening, a fuel discharge box communicating with said firing opening, the lower wall portion of said discharge box having a transversely extending front face provided with a recess, the forward face of said recessed portion having a circular cavity, a distributor plate fitted in said recess,

said distributor plate being provided with a recess in its central rear portion, a distributor head fitting in said recess, means for rigidly securing said distributor plate and distributor head together, said distributor head having a rearwardly extending circular lug received in said circular cavity forming a pivot for adjustment of said distributor plate and distributor head with respect to said discharge box in its adjusted position.

11. As a new article of manufacture, a fuel distributor comprising a flat plate having side and end faces, one of said end faces being provided with a recess intermediate said side faces, each of said side faces being formed with an outwardly curvate surface adjoining said recessed end face and the portions of said end face defining the recess being each provided with a slot 20 curved coaxial with the curvate surface of said side faces.

12. As a new article of manufacture, a fuel distributor comprising a plate having a flat surface and depending side and end walls, one of said end walls being provided with a recess intermediate said sidewalls, each of said side walls being formed with an outwardly curvate surface adjoining said recessed end wall, the portions of said end wall defining said recess having curved slots therethrough, the curvature of said slots being coaxial with the curvature of the curvate surfaces of said side walls.

13. A fuel distributing device comprising in combination, a distributor plate having a flat surface and depending side and end walls, one of said end walls being provided with a recess intermediate said sidewalls, each of said sidewalls being formed with an outwardly curvate surface adjoining said recessed end wall and a distributor head received in said recess, said distributor head rising above the surface of said plate, a plurality of jet openings in said distributor head directed over the surface of said plate, a circular lug formed with and projecting outwardly from the central portion of said distributor head rear wall, and means for securing together said plate and head in operative position.

14. In a furnace provided with a firing opening, a fuel discharge box communicating with said firing opening, the lower wall portion of said discharge box having a transversely extending front face, a fuel distributing device extending forwardly from said discharge box, said fuel distributing device having a rearward face abutting said transversely extending face, one of said faces being provided with a circular cavity and the other of said faces being provided with a circular lug arranged to fit snugly in said circular cavity partially holding said fuel distributing device and said discharge box in assembled relation and providing for relative pivotal movement therebetween about their common longitudinal center line, means for adjusting said distributing device about said pivot and means for rigidly securing said distributing device to said discharge box in its adjusted position.

15. In a furnace provided with a firing opening, a fuel discharge box communicating with said firing opening, the lower wall portion of said discharge box having a transversely extending front face provided with a recess, a fuel distributing device fitted in said recess and having its rearward face abutting the forward face of said recessed portion, said last named faces be-

- ing provided one with a circular cavity and the other with a circular lug arranged to fit snugly in said circular cavity partially holding said fuel distributing device and said discharge box in assembled relation and providing for relative pivotal movement therebetween about their common longitudinal center line, means for adjusting said distributing device about said pivot and means for rigidly securing said distributing device to said discharge box in its adjusted position.
16. In combination, a boiler furnace provided with a firebox having a firing opening, a fuel discharge box communicating with said firing opening, said discharge box being rigidly fixed to said boiler furnace and movable therewith, a fuel distributing device including a fuel receiving member extending forwardly from said discharge box and means for projecting fuel across said fuel receiving member, and means for pivotally adjusting said distributing device as a
- unit about its longitudinal center line in one of a number of positions independently of the movement of said boiler furnace and discharge box.
17. As a new article of manufacture, a fuel discharge box having a fuel receiving opening and a fuel discharge opening, the lower wall portion of said discharge box adjacent its discharge opening having a forward face extending transversely of the longitudinal axis of the discharge box, a recess in said forward face, a circular cavity formed in the forward face of the recessed portion of said lower wall portion, said cavity being disposed centrally in the forward face of said recessed portion, the opposite side faces of said lower wall portion defining said recess having concave surfaces coaxial with the longitudinal medial line of the lower wall portion.
